LINT CONDENSER

John C. Rogers and Redding Sims,
New Orleans, La.

Application March 20, 1937, Serial No. 132,079

6 Claims. (Cl. 19—156)

This invention relates to a lint condenser.

It is an object of the invention to provide a condenser for receiving the lint from a cotton gin, or linter, and compressing the same into a bat to be stored on a storage roller.

The ordinary type of condenser used with a gin or linter contains a rotatable drum, usually formed by mounting screen wire upon a cylindrical frame, all fixed on a central shaft and braced by longitudinal tie rods and spokes or braces radiated from the hub to the frame. This drum is mounted in a housing which directs the air stream coming from the linter brush and carrying the lint and as the air passes through the screen like drum the major portion of the lint is deposited upon the drum as it rotates and is collected on the roller at the rear side of the condenser. The air passing through the screen carries within it fine lint and dirt and is blown out through each open end of the cylinder into the room housing the gins or linters.

It is one object of the invention to provide a condenser drum composed of rings forming a framework or support for the foraminated material mounted thereon and which is mounted to rotate in a novel manner without the use of spokes, or longitudinal or radial braces, leaving the interior of the drum entirely open and thus making it possible to provide fixed shields within the drum to direct the air current into a flared conduit, also located in the drum with the ends of the drum sealed off so that the air may be confined and directed through a single outlet flue from which it may be conveyed away together with the lint and the dirt contained therein to the end that the lint and dirt will not be permitted to dissipate into the gin room.

It is another object of the invention to provide a novel type of condenser which may be applied to a single gin or linter so that the lint being delivered from the gin may be condensed and the air laden with dust and foreign matter may be confined and entrapped and conveyed to a point outside of the room and the dust nuisance within the room thus abated.

The type of condenser herein described is specially adapted for use with a single linter thus conducting to a thinner bat of lint being deposited on the drum and facilitating the disposition of the dust generated by the linter; furthermore the lint produced by each linter can be more uniformly regulated for each linter is provided with its one condenser.

Since the linter brush generating the air current works against back pressure caused by the

air having to pass through a bat of lint on the condenser, if a single condenser is employed with each linter a thinner bat of lint will be deposited on the condenser drum, thereby relieving the back pressure and requiring a less volume of air from the brush, thus making a slower brush speed possible; and for a similar reason less speed will be required of the suction fan by means of which air suction is created through the outlet flue leading from the condenser.

By the use of a condenser of the type described with each linter it has been found in practice that the amount of air exhausted from the gin room will be materially reduced to the end that the temperature within the room will not be so materially affected as is the case with a vacuum lint flue system now in common use.

With the above and other objects in view the invention has particular relation to certain novel features of construction, operation and arrangement of parts, an example of which is given in this specification and illustrated in the accompanying drawings, wherein:

Figure 1 shows an end view of the condenser.

Figure 2 shows a vertical cross sectional view taken on the line 2—2 of Figure 3.

Figure 3 shows a longitudinal sectional view, and

Figure 4 shows a fragmentary top plan view.

Referring now more particularly to the drawings wherein like numerals of reference designate the same parts in each of the figures, the numerals 1, 1 designate approximately rectangular end supports forming the supporting framework and having at their upper ends the cross bars 2, 2. Mounted on the framework between the end supports 1, 1 there is a foraminated drum 3 which may be made of wire mesh, but preferably of perforated sheet metal. The ends of the drum may be secured to the annular angle irons 4, 4, which form the sole means for maintaining the cylindrical shape of the screen whose inwardly turned flanges form tracks and the outwardly turned flanges of the angle irons 4 are formed into internally toothed ring gears 5, 5. The drum 45 may be supported on the rollers 6, 6, about which said tracks move. Those rollers are mounted on the shafts 7, 7, which extend longitudinally through the upper portion of the drum and which are mounted in the end bearings 8, 8 on opposite 50 sides of the rectangular end castings 9, 9 which, in turn, are supported on the respective cross bars 2.

The annular angle irons 4, 4 have formed on the periphery thereof radially outwardly project- 55

ing flanges 4a—4a, note particularly Fig. 3, and the foraminated drum or screen 3 lies within the boundary of said flanges. Thus, any lint collecting on the drum is out of the way of the internal 5 gear teeth and the flanges function not only to reinforce the ring but also insure against lint passing over the ends of the drum to said teeth.

A transverse shaft 10 extends through the lower portion of the drum and is mounted in the 10 inside bearings 11, 11 fastened to the rear legs of the end supports 1. This shaft 10 has the spur gears 12 fixed thereon which are in mesh with and drive the ring gears 5 thus rotating the drum on its supporting rollers 6. The outer end of 15 the shaft 10 has a sprocket wheel 13 fixed thereon over which a driving sprocket chain may operate to rotate the shaft 10. Other driving means for the drum than that specifically hereinabove described may be employed.

20 Above the drum there is a compression roller 14, preferably formed of wood, which extends approximately from end to end of the drum. This roller is fixed on a central shaft 15 whose ends extend beyond the roller and are located in the 25 vertical U-shaped bearings 16, 16, at the upper ends of the end castings 9. The ends of the roller 14 have the metal ferrules 14a, 14a having extended circular flanges 14b, 14b which roll on the tracks 4.

30 There are the roller supporting arms 17, 17, whose upper ends are pivoted to the upper ends of the end castings 9 and the lower ends of these arms have the upwardly open bearings 18, 18, to receive the ends of the shaft 19 on which the 35 bat receiving roller 20 is mounted. This roller cooperates with the drum 3 and is provided to receive the compressed bat of lint 21. The bat rolls about said roller 20 as indicated in Figures 1 and 2, the arm 17 permitting the roller 20 to 40 move outwardly from the drum as the roll enlarges. The roll of lint, when it reaches the desired size, may be removed and another roller 20 replaced for the removed one.

45 As the lint leaves the linter, it is carried by the air current through the lint flue 22 to the drum. This flue is enlarged adjacent the forward side of the condenser forming the hood 23 which is of a width approximately equal to the 50 length of the condenser and which extends upwardly to the compression roller 14. It confines the lint to the forward or exposed area of the drum 3. Within the drum there is fixed the housing 24, preferably formed of sheet metal and of a length substantially equal to the length of 55 the drum. This housing is of a frusto-conical form having its small end open and arranged close to the drum at one end with its larger, or discharge, end arranged at the lowest point of the drum and being there connected to the outlet flue 25. The fixed housing 24 is provided with 60 a longitudinal slot 26 approximately parallel with the axis of the housing and arranged opposite the lower portion of the flue 23. There is a vertical partition 27 of a length equal to the 65 length of the drum 3 and extending from the inside wall of the drum, opposite the roller 14, to the upper margin of the slot 26. There is a skirt, or platform, 28, also preferably formed of sheet metal and extending from the lower margin of the slot 26 forwardly to the inner wall of the 70 drum and in approximate alignment with the bottom of the hood 23, the drum, as it rotates, thus moving between the adjacent confronting margins of the bottom of said hood and said skirt 75 or apron.

The portions of the ends of the drum between the partition 27 and the hood 23 are closed by the end plates 29, 29, suitably secured to the framework.

The air from the linter and carrying the lint 5 cotton enters across the face of screen or drum uniformly distributed and deposits the lint on the drum passing onwardly through the slot 26 into the housing 24 and the air laden with dust, and a certain amount of fine lint, passes on toward the large or outlet end of the housing and into the outlet flue 25. Since the housing gradually enlarges toward its discharge end more capacity is provided for the constantly increasing amount of air to be handled and the dust carried 10 into the confined area in front of the partition 27 will gradually move downwardly until it is caught up by the air current from the conventional suction fan connected with the outlet flue 25 and 15 will be carried away thus preventing collection 20 of dust or other foreign matter in the condenser.

It will be noted that the housing 24 declines 25 toward its outlet end to facilitate the exit of the dust and foreign matter.

The ends of the housing 24 as well as the partition 27 and skirt 28 are suitably anchored to the end castings 9 and to the end cross bars 2 to provide a rugged structure.

30 The drum rotates in the direction indicated by arrow in Figure 2. The lint will be deposited, as above stated, in the form of a bat on that portion of the drum inclosed by the hood 23 and the bat will pass underneath the roller 14 and be compressed thereby and will move on to the roller 20 around which it will be rolled until the roll 35 has reached the required size. As the bat passes the roller 14, the air under compression from the linter brush as well as the air suction from the fan will be cut off from it.

The bat will thus be released from the drum 40 and will be free to accumulate on the roller 20.

A substantially closed conduit will thus be formed from the linter, through the condenser, to the point of discharge, thus preventing the escape of dust and free lint into the linter room. 45

By reason of the construction a completely enclosed condenser may be connected with each linter so that the linter may operate as heretofore but making it possible to collect all the air generated by the linter brush after this air has 50 deposited its lint on the drum or screen and only the air coming from the brush is required to be handled.

The lint passing through the screen into the housing and out through the lint flue 25 may 55 be collected and recovered.

It may be noted that the confined area defined by the partition 27, the housing 24 and the skirt 28 is such that any dust collecting therein will be aided by gravity as well as by air suction in 60 its movement toward the discharge, that is to say, the skirt declines toward the slot 26 and the axis of the housing 24 declines toward the point of exit and as is obvious the partition 27, is in an approximately vertical plane to the end that 65 there is no point in the confined area from which any material will have to be lifted against the force of gravity.

The drawings and description disclose what is now considered to be a preferred form of the 70 invention by way of illustration only, while the broad principle of the invention will be defined by the appended claims.

What we claim is:

1. A condenser comprising a supporting frame- 75

- work, a rotatable foraminated cylindrical screen mounted on the framework, means for rotating the screen, a flue having an inlet duct and an outlet duct and including a conical shaped housing 5 located wholly within the screen and whose large end terminates at the outlet duct, a restricted area only of the screen spanning said flue and means cooperating with said housing to confine the passage of air through the screen to that portion of the screen spanning the flue whereby lint carried by the air current passing through the flue will be deposited on that portion of the screen exposed to said current.
2. In a condenser a cylindrical screen, a fixed housing in the screen having an entrant side opening and being flared toward its discharge end, the small end of the housing being open, a partition extending upwardly from the entrant opening to the inner wall of the drum and a platform 15 or skirt extending from beneath the entrant opening to the inner wall of the drum, said platform diverging outwardly with respect to the partition the surface area of the screen between said partition and said skirt constituting the entire active portion of the screen.
3. A condenser for lint cotton and the like comprising a framework, a rotatable, cylindrical screen mounted on the framework, a flue, a housing located wholly within the screen and beneath the axis of the screen and which is flared toward its discharge end, the axis of the housing declining toward said discharge end and the small end of the housing being open, said housing having a longitudinal, side entrant opening approximately 20 parallel with the axis of the housing, deflectors above and beneath said entrant opening extending from end to end of the screen and extending from the margins of said entrant opening to the inner wall of the screen, said housing and deflectors forming an enclosed space within the screen which constitutes the entire active area of the screen and which forms a continuation of the flue, the construction and arrangement providing a chamber on the outer side of the active area of the screen and limited thereto.
4. A condenser for lint cotton and the like comprising a frame work, a rotatable cylindrical screen mounted on the frame work, a flue, a housing including a suction conduit located wholly 25 within the screen and flared towards its discharge end, the axis of the suction conduit declining towards said discharge end and the conduit having a longitudinal entrant opening approximately parallel with said axis, deflectors above and beneath said entrant opening extending from end to end of the screen and from the entrant opening to the inner wall of the screen, said conduit and deflectors forming an enclosed space within the screen which forms a continuation of the flue, 10 that portion of the screen lying between the deflectors constituting the entire active area of the screen.
5. In a condenser for fibrous material, a rotatable foraminated drum forming a screen, a fixed housing within the screen having a suction conduit formed with an entrant side opening, said conduit being located below the axis of the drum and the lower wall of the conduit declining towards its discharge end, an inlet air flue exterior 20 of the drum coaxing with said housing to confine a restricted area of the screen therebetween constituting the active area of the screen, said housing including deflectors projected from said entrant opening to points adjacent the inner wall of 25 the screen, said deflectors encompassing the entire active area of the screen.
6. A condenser comprising a rotatable screen, means defining corresponding chambers on the outer and inner sides of the screen with that portion of the screen therebetween constituting the active portion of the screen and forming a partition between the chambers so that the total amount of air in the outer chamber is exposed to the active surface of the screen and may pass 30 therethrough to the inner chamber, a suction line connected through the end of the condenser to the lower portion of the inner chamber and having an axially-extending entrant opening communicating the chamber with the line, the means 35 forming a chamber on the inside of the screen including means operating to deflect the air passing from the outer to the inner chamber in a generally downward direction to the entrant opening of the suction line so that matter passing 40 through the screen will be assisted by gravity 45 in being carried into the suction line.

JOHN C. ROGERS.
